CLAIM

The ornamental design for a storage cabinet as shown and described.

DESCRIPTION

FIG. 1 is a top front left perspective view of a storage cabinet of the present invention;

FIG. 2 is a top front right perspective view thereof;

FIG. 3 is a front view thereof;

FIG. 4 is a left side view thereof;

FIG. 5 is a right side view thereof; and,

FIG. 6 is a top view thereof.

The portions of the storage cabinet illustrated in broken lines form no part of the claimed design.
